(57) **CLAIM**

The ornamental design for a tray for storing optical fiber, as shown and described.

DESCRIPTION

FIG. 1 is a front perspective view of a tray for storing optical fiber showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of area 9 in FIG. 3;

FIG. 10 is a cross-sectional view taken in the direction of line 10-10 in FIG. 9; and,

FIG. 11 is a cross-sectional view taken in the direction of line 11-11 in FIG. 7.

The broken lines in the drawings depict portions of the tray for storing optical fiber that form no part of the claimed design. The dot dashed lines shown in FIGS. 3, 9, and 10 denote the boundaries of the detail view area and form no part of the claimed design.
